(57) **CLAIM**

The ornamental design for a laser hair growth cap, as shown and described.

DESCRIPTION

FIG. 1 is a front elevational view of a Laser hair growth cap showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is an enlarged view of portion 8 shown in FIG. 7; and, FIG. 9 is a perspective view showing a condition in use with a clipper for fixing the cap on the head.

The broken lines depicting a clip in FIG. 9 represent an environmental structure and form no part of the claimed design.
